COMBINED BOTTLE AND MEASURING CUP

Jack Skolnik, New Rochelle, N.Y., and Robert H. Kries,
Westport, Conn., assignors to Richardson-Merrell Inc.,
New York N.Y., a corporation of Delaware

Filed Mar. 14, 1967, Ser. No. 6,220

Term of patent 14 years

(Cl. D9—10)

FIG.1

FIG.2

FIG.3

FIG. 4

FIG. 5

FIG. 6

FIGURE 1 is a perspective view of a combined bottle and measuring cup embodying our new design;

FIGURE 2 is another perspective view taken 45° from the position seen in FIGURE 1;

FIGURE 3 is a top plan;

FIGURE 4 is another perspective view;

FIGURE 5 is an enlarged fragmentary elevational view of the upper portion partly in section; and

FIGURE 6 is an enlarged fragmentary elevational view of the upper portion partly in section and taken 45° from the position seen in FIGURE 5.

We claim:

The ornamental design for a combined bottle and measuring cup, substantially as shown.
